Filed Mar. 25, 1970, Ser. No. 22,059

Term of patent 14 years

Int. Cl. D15—07

U.S. Cl. D67—3

FIG. 2.

FIG. 1.

FIG. 1 is a front perspective view of a domestic refrigerator case embodying our new design, the diagonal white shade lines on the black door for the compartment at the top of the interior indicating translucency;

FIG. 2 is a second front perspective view of the refrigerator case showing the compartment door in an open position.

The faces of the refrigerator case not shown are conventionally plain.

The characteristic feature of the design is the illustrated interior of the refrigerator.

We claim:

The ornamental design for a domestic refrigerator case, as shown and described.
